Filed June 7, 1965, Ser. No. 461,897

5 Claims. (Cl. 74—194)

ABSTRACT OF THE DISCLOSURE

A base rotatably mounting a rotor, said rotor further having a circular socket, formed with a sidewall arcuately inclined toward said axis, a bracket pivotally mounted upon a sidewall of said base, and rotatably mounting a wheel; said wheel having frictional engagement with said inclined sidewall, whereby a driving force may be applied to either said rotor or said wheel, to afford transmission of a drive from either of said elements to the other of said elements, and whereby the pivotal mounting of said bracket affords an adjustment of the frictional engagement upon said arcuate surface to and from said axis to afford a determination of the speed of the drive to be transmitted.

This invention relates to mechanisms for reversibly transmitting a rotary drive from one rotatably journaled member to another and particularly to such mechanisms as are designed to afford adjustment to vary the speed of the drive so transmitted.

An object of the invention is to provide a rotor journaled in a base, said rotor having a surface inclined to its axis of rotation in the base, and to provide a shaft journaled in a bracket with a wheel having a peripheral area of said wheel in driving or drivable engagement with said inclined surface, so that by such engagement, either rotatable member may impart to, or receive from, the other a rotatable driving force.

A further object is to provide means to advance said wheel along said inclined surface toward said axis or retract said wheel from said axis to respectively accelerate or decelerate the transmitted drive.

Still another object is to incline said surface arcuately, and to provide a pivot to mount the bracket, so that arcuate travel of said bracket about the pivotal axis of the pivot causes the advance or retraction of said wheel.

Still another object is to adapt said base to receive said pivot and thus pivotally mount the bracket.

These and various other objects are attained in the construction hereinafter described and illustrated in the accompanying drawing, wherein:

FIG. 1 is an elevational, sectional view on line 1—1 of FIG. 2.

FIG. 2 is a plan view in partial section of the device on line 2—2 of FIG. 1.

FIG. 3 is an elevational sectional view on line 3—3 of FIG. 1.

FIG. 4 is a partial view in partial section illustrating the construction of said shaft wheel, and bracket.

FIG. 5 is a line on 5—5 of FIG. 4, further illustrating said construction.

In these views the reference character 1 designates the base which may be formed with a shank 2. Any conventional means may be employed to mount the base, depending upon the environment in which the device is used. However, its anticipated uses are so numerous that only one simple mounting means is shown, employing screws 3 to mount the device to a plate or wall 4.

The base is socketed as at 5, said socket having an annular sidewall 6, and bottom wall 7. A hole 8 is formed in said bottom wall. A rotor 9 is received in said socket 5, and has a shank 10 rotatably journaled in the hole 8.

2

A square shaft 11 serves to interconnect the shank of the rotor with any properly adapted device for transmission of a rotary drive from or to the rotor. Said square shaft may be of course, splined, slotted, or otherwise adapted for drive transmission. The rotor is interiorly formed with a recess 12 having an annular sidewall 13 arcuately inclined from the axis of rotation of the rotor.

The base 1 is formed with diametrically opposed flats 14 on its annular sidewall. Said flats are apertured as at 15 to receive a shouldered hex headed screw 16. The inner end portion of said screw threadedly engages in a mounting arm 17 of a bracket 18. Said bracket is formed with a bearing 19 apertured to rotatably journal the shaft 20 of a circular member, such as a wheel 21. Said wheel preferably carries at its periphery an annular rubber "tire" which naturally, has a circular surface 22, and a peripheral area of said tire engages the arcuately inclined sidewall 13 in the rotor 9 to transmit or receive a drive, depending upon whether the rotor 9 or wheel 21 is being driven.

A sheath 23 is formed with an annular lip 24 whereby it is assembled to the bracket 18 by a nut 25 threadedly received on the bearing 19. A transmission element 26 is rotatably drivable in the sheath. The sheath 25 and transmission element 26, may both be flexible if desired. The shaft 20, carrying the wheel 21 may be adapted in any suitable manner for driving interconnection with said transmission element 26 as at 27.

As may now be seen, the bracket 18 may be adjustably, moved in arcuate travel about the axis of the pivot screw 16 by turning said screw to afford such adjustment, to advance the wheel along the arcuately inclined sidewall 13 toward the axis of rotor rotation, which will accelerate the transmitted drive. Said bracket may, conversely, be arcuately moved to retract the wheel along said sidewall 13 from said axis of rotation to decelerate the transmitted drive. When the screw 16 is turned to draw the bracket mounting arm 17 into tight frictional engagement with the flat surface 14, such engagement resists undesirable movement of the bracket about the pivotal axis of the screw 16.

It is important that the pivotal axis of the screw 15 approximately intersect the plane of the drive wheel 21, and that the locus of the radius of the arcuately inclined sidewall 13 be situated at said intersection in order to maintain approximately uniform frictional engagement of the wheel 20 on the interior surface of said sidewall regardless of where on said surface said engagement occurs. If said locus were not so situated, arcuate travel of the wheel 21 could disengage the wheel from said surface.

Clearly, if a drive is applied to the rotor, it will rotatably drive the wheel 21, and if a drive is applied to the wheel, it will rotatably drive the rotor. Regardless of which element is driving which, the direction of such drive may be reversed by mounting the bracket 18 on the opposite side of the base 1 from that shown in the drawing.

What I claim is:

1. In mechanism to reversably transmit a rotary drive,
  - (a) a rotor rotatably drivable about a first axis of rotation said rotor being formed with
  - (b) an annular surface arcuately inclined with respect to said axis,
  - (c) a shaft rotatably drivable about a second axis of rotation, said shaft having concentrically disposed thereon,
  - (d) a member having a circular surface, said shaft being juxtaposed to said rotor to frictionally engage an area of said circular surface with said inclined annular surface to thereby transmit or receive a rotatable drive,
  - (e) adjusting means adapted to afford advance and retraction of said circular surface along the arcuately inclined annular surface toward or from said first

axis to respectively accelerate or decelerate the velocity of said drive,
 (f) a base adapted to journal said rotor,
 (g) a bracket adapted to journal said shaft,
 (h) whereby a rotative drive applied to either said 5
 rotor or said shaft transmits said drive to the other
 said member through said frictional engagement,
 (i) a socket formed in said base,
 said rotor being rotatable within said socket,
 said socket having an annular sidewall and a bot- 10
 tom wall, said bottom wall being apertured,
 and said rotor having a shank rotatably received
 in said aperture to receive or transmit a drive
 to said bottom wall.

2. In a mechanism as set forth in claim 1, said adjust- 15
 ing means being a pivot element interconnecting said base
 and said bracket whereby said bracket and said circular
 surface may have desired arcuate travel about the pivot
 axis of said pivot to effect said advancement toward or
 retraction from said first axis of rotation and 20
 (j) means to resist undesired arcuate travel of said
 bracket.

3. In a mechanism as set forth in claim 1, said annular
 sidewall having a flat surface, said pivot element extending
 through said sidewall at said flat surface, said bracket
 being pivotally carried by said pivot element and jour- 25
 nalling said circular member in position to effect said
 frictional engagement of said circular surface and said in-
 clinod surface.

4. In a mechanism to reversably transmit a rotary drive, 30
 (a) a rotor rotatably drivable about a first axis of ro-
 tation, said rotor being formed with
 (a) said annular surface inclined with respect to said
 axis,
 (b) said annular surface inclined with respect to said 35
 rotation, said shaft having concentrically disposed
 thereon,
 (d) a member having a circular surface, said shaft be-
 ing juxtaposed to said rotor to frictionally engage an

area of said circular surface with said inclined annular surface to thereby transmit or receive a rotatable drive.

(e) adjusting means adapted to afford advance or re-
 traction of said circular surface along the inclined
 annular surface toward or from said first axis to re-
 spectively accelerate or decelerate velocity of said
 drive,

(f) a base adapted to journal said rotor,
 (g) a bracket adapted to journal said shaft,
 (h) whereby a rotative drive applied to either said
 rotor or said shaft transmits said drive to the other
 said member through said frictional engagement.

(i) a socket formed in said base,
 said rotor being rotatable within said socket,
 said socket having an annular sidewall and a bot-
 tom wall, said bottom wall being apertured,
 and said rotor having a shank rotatably received
 in said aperture to receive or transmit a drive to
 said bottom wall.

5. In a mechanism as set forth in claim 4, said pivot
 element extending through said sidewall at said flat sur-
 face, said bracket being pivotally carried by said pivot
 element and journaling said circular member in a position
 to effect said frictional engagement of said circular sur- 20
 face and said inclined surface.
